UNITED STATES PATENT OFFICE.

ROB ROY McGREGOR, OF COVINGTON, TENNESSEE.

TRUSS.

No. 910,303.

Specification of Letters Patent.

Patented Jan. 19, 1909.

Application filed January 6, 1908. Serial No. 409,502.

To all whom it may concern:

Be it known that I, ROB R. McGREGOR, a citizen of the United States, residing at Covington, in the county of Tipton and State of Tennessee, have invented certain new and useful Improvements in Trusses; and I do hereby declare the following to be a full, clear, and exact description of the invention, such as will enable others skilled in the art 10 to which it appertains to make and use the same.

My invention relates to trusses for hernia, etc., and has for its object to provide a simple and inexpensive device of this nature which 15 is adjustable to suit various requirements and is perfectly fitted for the purposes for which it is designed.

The invention consists in the features of construction and combinations of parts hereinafter described and specified in the claims.

In the accompanying drawing illustrating the preferred embodiment of my invention: Figure 1 is a perspective view of the truss. Fig. 2 is an enlarged section through the 25 clamping disks and bands and strips arranged between them. Fig. 3 is a plan view of one of the pads. Fig. 4 is a longitudinal section thereof. Fig. 5 is a cross section, and Fig. 6 is a detailed view of an attachment 30 for use in place of the pad-carrying strips.

Referring more particularly to the drawing, 1 and 2 designate the truss-bands of resilient strips. Said bands are curved and each is provided with perforations 1^a, 2^a 35 respectively in one of its ends. Said perforations are engaged by a screw pin or bolt 3 connecting two concavo-convex disks 4 and 5. Also mounted on said pin or bolt are two short curved resilient strips 6 and 7, each 40 carrying a compression pad 8 and 9, respectively, and having a series of perforations 6^a, and 7^a, respectively, any one of which may be engaged by said pin. The arc of the concavity and convexity of said disks is of a 45 smaller radius than the curvature of said bands and strips. The ends of said bands 1 and 2 and strips 6 and 7 project slightly beyond the edges of the disks whereby they are clamped by said edges when said disks 50 are drawn together by the pin 3.

It will be observed that the construction and arrangement of the bands and pads is such that said pads exert pressure upward as well as backward. This pressure may be 55 increased or lessened by adjusting the screw pin to draw the disks closer together or sepa-

rate them farther apart. The bands being resilient hold themselves in place without requiring any buckles or lacing strings. Buttons 10 are secured to the free ends of said bands to receive an elastic connection if desired although this is not necessary. Said bands are preferably offset or bent as at 11 near the clamping disks to permit the strips 6 and 7 to be swung upward, if desired, to 65 raise the pads into line with the bands 1 and 2 without bringing said pads below said latter bands. The strips 6 and 7 may be adjusted independently, that is, one may be made long and the other short or both be 70 adjusted the same length as will best suit requirements.

Each pad is generally elliptical in shape and is concave near the center on the side next to the body while the outer portion or 75 edge of said side is convex or rounded. The lower end 12 is left full to give the necessary support and the outside edge 13 which fits in one of the groins is made thin, as shown, the advantages of which will be apparent to 80 those skilled in the art.

The strip 14 carrying a cup 15 for use in the treatment of prolapsus may be substituted for the pad-carrying strips 6 and 7.

The bands 1 and 2 are not long enough to 85 bear upon the spine but hold themselves in place by reason of their resiliency.

I claim:

1. In a truss, the combination with resilient bands which are curved in opposite directions, 90 of a resilient strip bowed away from the body and carrying a supporting device, and means to secure said strip to said bands which also serves for connecting said bands together.

2. In a truss, the combination, with resilient bands, and resilient curved strips bowed away from the body and carrying pads, of a pair of disks and means to adjustably secure said strips and bands between said disks. 100

3. In a truss, the combination, with resilient curved bands and resilient curved strips carrying pads, of a pair of concavo-convex disks, and means to secure said strips and bands between said disks.

4. In a truss, the combination, with resilient curved bands and resilient curved strips carrying pads, of a pair of concavo-convex disks, the arc of said concavity and convexity having a less radius than the curvature of 110 said strips and bands, and means to secure said strips and bands between said disks.

5. In a truss, the combination, with resilient curved bands, each having a perforation therein, and resilient curved strips carrying pads, each of said strips having a series of perforations therein, of a pair of disks, and a set screw passed through said disks, the perforations in said bands, and certain of the perforations in said strips for the purpose specified.
- 10 6. In a truss, the combination, with resilient curved bands, each having a perforation therein, and resilient curved strips carrying pads, each of said strips having a series of perforations therein, of a pair of concavo-convex disks, and a set screw passed through said disks, the perforations in said bands and certain of the perforations in said strips for the purpose specified.
- 15 7. In a truss, the combination, with resilient curved bands having buttons on the ends for fastening a suitable connecting piece, of a resilient curved strip carrying a supporting device, and means to fasten said strip and bands together in proper position.
- 20 8. In a truss, the combination, with resilient curved bands, and resilient curved strips carrying pads, of a pair of disks and means to adjustably secure said strips and bands between said disks, said bands being offset upwardly near said disks for the purpose specified.
- 25 9. In a truss, the combination, with supporting bands, of a pair of resilient strips depending from said bands and bowed away from the body, means to clamp the ends of said strips which are connected to the bands whereby the lower ends of the strips are pressed upward and rearward, and a pair of pads, each generally elliptical in shape and having its side next to the body concave, the inner edge of each pad being thinner than its outer edge and its lower end fuller than its upper end for the purposes specified.

In testimony whereof, I affix my signature, in presence of two witnesses.

ROB ROY McGREGOR.
